UNITED STATES PATENT OFFICE.

WILLIAM GOODELL, OF MILLINOCKET, MAINE.

PAPER-PULP-LAP-FOLDING MACHINE.

1,231,520.

Specification of Letters Patent. Patented June 26, 1917.

Application filed November 15, 1915. Serial No. 61,605.

To all whom it may concern:

Be it known that I, WILLIAM GOODELL, a citizen of the United States, residing at Millinocket, in the county of Penobscot and 5 State of Maine, have invented certain new and useful Improvements in Paper-Pulp-Lap-Folding Machines; and I do hereby declare the following to be a full, clear, and exact description of the invention, such as will 10 enable others skilled in the art to which it appertains to make and use the same.

The invention relates to a paper pulp lap folding machine.

The object of the present invention is to 15 provide a simple, practical, and comparatively inexpensive paper pulp lap folding machine adapted to receive the sheets or laps of paper pulp as the same are discharged from a wet machine and equipped with a 20 roller bed for receiving the paper pulp lap and with means operating in timed sequence for successively folding the sheets of paper pulp or laps to the required size whereby hand folding as now practised in paper 25 pulp mills may be entirely eliminated.

With these and other objects in view the invention consists in the construction and novel combination and arrangement of parts hereinafter fully described, illustrated in 30 the accompanying drawings and pointed out in the claims hereto appended, it being understood that various changes in the form, proportion and minor details of construction may be resorted to without departing from 35 the spirit or sacrificing any of the advantages of the invention.

In the drawing

Figure 1 is a plan view of a paper pulp lap folding machine constructed in accordance 40 with this invention.

Fig. 2 is a vertical sectional view taken substantially on the line 2—2 of Fig. 1,

Fig. 3 is a side elevation of the folding machine,

Fig. 4 is a vertical sectional view on the line 4—4 of Fig. 1 illustrating the mechanism for actuating the outer longitudinal folding devices,

Fig. 5 is a similar view on the line 5—5 of 50 Fig. 2 illustrating the mechanism for actuating the inner longitudinal folding devices,

Fig. 6 is a sectional view illustrating the mechanism for actuating the transverse folding devices,

Fig. 7 is a detail view of the stop wheel 55 of the mechanism for operating the movable section of the roller bed,

Fig. 8 is a detail view of the double cam of such mechanism,

Fig. 9 is a detail view of one of the stop 60 wheels of the mechanism for operating the folding devices,

Fig. 10 is a detail view of the cam of such mechanism.

Like numerals of reference designate corresponding parts in all the figures of the drawings.

In the accompanying drawings, in which is illustrated the preferred embodiment of the invention, the paper pulp lap folding 70 machine comprises in its construction a main frame 1 of substantially rectangular form and of any desired construction and provided with suitable bearings for a pair of spaced transversely disposed shafts 2 75 and inner and outer longitudinally disposed shafts 3 and 4 arranged in pairs as clearly illustrated in Fig. 1 of the accompanying drawings. The shafts 2, 3, and 4 are provided at intervals with arms 6 and 7 and 80 they constitute folding devices for successively folding a sheet or lap of paper pulp. The folding devices are oscillated in timed sequence as hereinafter fully described. The shafts 2 are located in a horizontal plan 85 slightly above the shaft 4 while the intermediate longitudinal shafts 3 are located slightly below the plan of the shafts 4. The arms 7 have angle bends 8 to arrange their terminal portions 9 at right angles to the 90 body portions of the rods as shown. The transverse shafts 2 are provided with central offset bends 10, which are adapted to lengthen the discharge hole 11 hereinafter described so that the folded lap may fall 95 through without clogging at the ends and the intermediate longitudinal shafts 3 are located at the ends of the bends 10 which extend outwardly as shown in Fig. 1 when the folding devices are in their normal or initial position. By this arrangement an open oblong space 11 is formed at the center of the folding machine. The sheets of paper pulp, which are approximately six feet square, when folded are discharged at the 100 central open space. The shafts 2 are successively operated to fold a sheet of paper pulp transversely along the lines of the

105

shafts 2 which are spaced approximately equidistant from each other and from the ends of the machine.

The outer longitudinal shafts 4 are then operated simultaneously to fold the sheets longitudinally along the lines of the said shafts 4, after which the intermediate or inner longitudinal shafts 3 are simultaneously operated to fold the sheets centrally and cause the folded sheets to fall through the open space 11. The paper pulp lap folding machine is equipped with a roller bed composed of end and intermediate sections, the rollers 12 of the end sections being mounted in stationary bearing brackets 13 or other supporting means and the rollers 14 of the intermediate section being mounted in bearings or suitable supports 15 and carried by a vertically movable frame 16 operated in a timed sequence with the folding devices and adapted to be elevated to the plane of the rollers of the end section when a sheet of paper pulp is deposited on the machine and lowered out of the way of the folding devices after the sheet has been arranged on the machine. The rollers project slightly above the plane of the arms of the folding devices and the rollers 14 of the intermediate section of the roller bed are carried downwardly below the plane of the arms of the said folding devices and out of the way of the same so that the paper pulp may be folded in a flat condition without the folding being affected by the rollers of the bed. The vertically movable frame may be rectangular as shown in Fig. 1 of the drawings and it is provided at opposite sides with uprights 17 connected at their upper ends by a top member 18 and provided at opposite sides with horizontal pins 19. The vertically movable frame is connected by links or rods 20 with crank elements 21 and 22 of an overhead transverse shaft 23. The lower ends of the links or rods 20 are connected with the horizontal pins 19 and the crank elements 21 and 22 of the crank shaft 23 while being shown in the form of simple cranks may be of any other form as will be readily understood. The crank element 22 is eccentrically connected with a stop wheel 24 mounted on the inner end of a horizontal shaft 25 which has a sliding clutch section 26 for engaging a clutch face 27 of a sprocket wheel 28 whereby when the clutch section is engaged with the sprocket wheel, the shaft 25 will be rotated to actuate the vertically movable frame. The clutch section 26 may be slidably interlocked with the shaft in any desired manner and it is connected with an upwardly extending arm 29 of an approximately T-shaped lever 30 fulcrumed at its angle and having inwardly and outwardly extending horizontal arms 31 and 32. The stop wheel 24 is provided at diametrically opposite points with notches or recesses 34

of substantially semi-circular shape to enable the arm 31 of the lever 30 to engage with the said notches 34 and to be readily disengaged therefrom. The upwardly extending arm 29 is connected with a coiled spring 35 secured to the main frame or other suitable support and adapted to maintain the clutch section 26 normally out of engagement with the sprocket wheel 28 and also hold the outer arm 32 of the T-shaped lever 30 against a flange or rim 36 of a cam gear wheel 37. The cam gear wheel 37 which is preferably in the form of a sprocket wheel is provided at the annular flange or rim 36 with cams 38 and 39 arranged to successively engage the arm 32 of the T-shaped lever 30 to move the arm 31 out of engagement with the stop wheel and simultaneously carry the sliding clutch section into engagement with the clutch face 27 of the gear wheel 28 which is preferably in the form of a sprocket wheel and which is continuously rotated by the means hereinafter described.

This operation of the T-shaped lever rotates the shaft 25 and the stop wheel 24 which maintains the lever 30 out of engagement with the notches 34 until the next notch is carried to a point above the arm 31. The shaft 25 is rotated during this time by the engagement of the clutch section or members. As soon as the stop wheel 24 has made one-half a revolution, the other notch or recess 34 is carried to a position above the arm 31 which is moved into the notch 34 by the spring 35 thereby withdrawing the clutch section 26 from engagement with the clutch face 27 of the sprocket wheel 28 and stopping the shaft 25. This half revolution of the wheel 24 and the shaft 23 elevates the movable section of the roller bed which remains in an elevated position while the pulp sheet is being transferred to the folding machine. When this operation has been effected the wheel 37 through its cam 39 again operates the T-shaped lever and permits another half revolution of the shaft 23 which lowers the movable section of the roller bed from its elevated position to its position below the folding devices. In order to provide an easy movement of the frame 16, the movable section of the roller bed is counterbalanced by suitable weights 40 connected with one end of a cable 41 or other suitable flexible connections which is arranged on an overhead pulley 42 and which is connected at its other end with the frame 16 at the center of the transverse member 18.

Any other suitable means may of course be employed for counterbalancing the vertically movable section of the roller bed and for securing an easy operation thereof in moving the same to and from the horizontal plane of the stationary sections.

Each of the transversely disposed shafts 2 of the folding devices is equipped at one

end with a pinion 43 which meshes with a vertically movable rack bar 44 operating in suitable guides and connected by a rod or pitman 45 with an eccentrically arranged pin 46 of a stop wheel 47 adapted to make one complete revolution for reciprocating the rack bar 44 which is vertically disposed. By reciprocating the rack bar 44 the folding devices are oscillated first in one direction 10 to fold the sheet of pulp and then in the opposite direction to return them to their initial position. The stop wheel 47 is provided with a single notch or recess 48 and it is mounted on a shaft 49 having a slidable 15 clutch section 50 adapted to engage a clutch face 51 of a sprocket wheel 52. The slidable section is connected with a T-shaped lever 53 constructed similarly to that heretofore described and adapted to coöperate with the 20 stop wheel 47 and with a cam wheel 54 having a single cam 55 on its annular flange or rim 56. The wheel 54 is in the form of a sprocket wheel similar to the cam wheel heretofore described and the cam of the 25 cam wheel 54 of the two transverse shafts 2 is timed to secure a proper operation of the folding devices to successively fold the sheet of pulp from the ends of the machine over the central portion as before described. 30 The T-shaped lever 53 is connected with a coiled spring 57 which operates similarly to that heretofore described in moving the T-shaped lever into the notch of the stop wheel and withdrawing the sliding clutch from the 35 sprocket wheel 52. The outer longitudinal shafts 4 are provided at one end with pinions 58 which mesh with rack bars 59 operating in suitable guides and connected by rods 60 and 61 with crank elements 62 40 and 63 of a crank shaft 64 having an extension 65 on which is mounted a slidable clutch section 66 adapted to engage a clutch face 67 of a sprocket wheel 68. The slidable clutch section is operated by a T-shaped 45 lever 69 controlled by a cam wheel 70 and a stop wheel 71. The stop wheel 71 which is constructed similar to the stop wheel 47 is mounted on the shaft 64 and the cam wheel 70 which is similar in construction to the 50 cam wheel 54 is mounted on a shaft 72. The cam wheel 70 is timed to secure a proper operation of the folding devices with which it is connected.

The inner or intermediate longitudinal shafts which effect the final folding and the discharge of the folded sheets of paper pulp are provided with intermeshing gears 74, 75 and arm 76 being connected with the gear 74 and with the shafts 3 on which such gear 60 is mounted and adapted to be oscillated for simultaneously rotating the said shafts 3. The arm 76 is connected by jointed rods or members 77 and 78 with a crank 79 of a shaft 80 carrying a stop wheel 81 of mechanism 65 having a sprocket wheel 83 and

a cam sprocket wheel 84 and constructed similar to the mechanism for operating the vertically movable rack bars heretofore described. The cam of this mechanism is properly timed and when the mechanism is 70 operated the arm 76 will be oscillated and the inner longitudinal rock shafts 3 will be simultaneously operated to effect the final fold of the paper pulp sheet and the discharge of the latter through the space 11. 75

The actuating sprocket wheels of the several sets of mechanism and the cam sprocket wheels of the same are arranged in two horizontal rows as clearly illustrated in Fig. 3 of the drawings and are connected by 80 sprocket chains 85 and 86 which are also arranged on driving sprocket wheels 87 and 88.

The driving sprocket wheels 87 and 88 are connected by sprocket gearing 89 properly proportioned to regulate the speed of the cam wheels above mentioned and time their operation when suitably arranged on the sprocket chain 86. The driving sprocket 87 may be connected with a motor or with 90 the wet machine by any suitable means for operating the paper pulp lap folding machine.

The sprocket chains are engaged by tightener rollers 90 and 91 arranged at intervals. 95

What is claimed is:—

1. A paper pulp lap folding machine including folding means, means for supporting a sheet of paper pulp above and out of contact with the folding means while the paper pulp is being delivered from a wet machine to the folder, and mechanism operating in timed sequence for operating the folding means to fold the sheet of paper pulp successively. 100

2. A paper pulp lap folding machine including folding means, rollers for supporting a sheet of paper pulp above and out of contact with the folding means while the paper pulp is being delivered from a wet 110 machine to the folder, and mechanism operating in timed sequence for operating the folding means to fold the sheet of paper pulp successively. 105

3. A paper pulp lap folding machine including folding means, rollers for supporting a sheet of paper pulp above and out of contact with the folding means while the paper pulp is being delivered from a wet machine to the folder, the rollers being movable upwardly and downwardly to arrange them below the folding means, and mechanism operating in timed sequence for operating the folding means to fold the sheet of paper pulp successively. 115

4. A paper pulp lap folding machine including folding means, rollers for supporting the paper pulp above and out of contact with the folding means while the said paper pulp is being delivered from a wet machine 130

to the folder, the rollers being permanently mounted in a projecting position and other of the rollers being movable upwardly and downwardly to arrange them below the plane of the folding means.

5. A paper pulp lap folding machine including vibratory rock shafts provided with arms and arranged to operate at right angles to one another in timed sequence for effecting successive folds in a sheet of paper pulp in two directions, supporting devices operating between the said arms for supporting a sheet of paper pulp in an elevated position above the said arms while the paper pulp is being delivered from a wet machine to the folder.

6. A paper pulp lap folding machine including spaced transversely disposed rock shafts provided with means for engaging a sheet of paper pulp to fold the same and inner and outer longitudinal rock shafts provided with means for engaging the sheet of paper pulp, means for operating the rock shafts in timed sequence to fold the sheet 25 of paper pulp both longitudinally and transversely, and supporting devices operating between the arms for supporting a sheet of paper pulp above and out of contact with the said arms while the paper pulp is being 30 delivered to the folder from a wet machine.

7. A paper pulp lap folding machine including spaced transverse rock shafts provided at a point intermediate of their ends with offset bends and having arms arranged 35 at intervals for engaging the paper pulp sheet and inner and outer longitudinal rock shafts spaced apart and provided with arms arranged at intervals for engaging the sheet of paper pulp, means for operating the rock 40 shafts in timed sequence to successively actuate the transversely disposed rock shafts and simultaneously operate the members of the outer longitudinal rock shafts and finally simultaneously actuate the members of the 45 inner longitudinal rock shaft, and rollers operating between the said arms to support the paper pulp in an elevated position above the arms while the paper pulp is being delivered to the folder from a wet machine, 50 some of the rollers being mounted in a permanently projecting position and other of the rollers being movable to and from a projecting position.

8. A paper pulp lap folding machine including rock shafts provided with spaced arms for engaging the sheet of paper pulp and supporting means consisting of rollers projecting between the paper engaging arms.

9. A paper pulp lap folding machine including rock shafts provided with spaced arms for engaging the sheet of paper pulp and supporting means consisting of rollers projecting between the paper engaging arms, and means for moving the rollers upwardly

and downwardly to carry the same to and 65 from a projecting position.

10. A paper pulp lap folding machine including rock shafts provided with spaced arms for engaging the sheet of paper pulp and means for supporting the paper pulp sheets including rollers projecting upwardly between the arms, said supporting means having some of the rollers mounted for upward and downward movement to carry them to and from the projecting position 75 and other rollers permanently mounted in a projecting position.

11. A paper pulp lap folding machine including rock shafts provided with spaced arms for engaging the sheet of paper pulp 80 and means for supporting the paper pulp sheets including rollers projecting upwardly between the arms, said supporting means being composed of intermediate and end sections, the intermediate section being movable upwardly and downwardly to carry the rollers to and from a projecting position.

12. A paper pulp lap folding machine including rock shafts provided with spaced arms for engaging the sheet of paper pulp 90 and means for supporting the paper pulp sheets including rollers projecting upwardly between the arms, said supporting means being composed of intermediate and end 95 sections, the intermediate section being movable upwardly and downwardly to carry the rollers to and from a projecting position and means operating in timed sequence for raising and lowering the intermediate section of the supporting means and for successively operating the rock shafts.

13. A paper pulp lap folding machine including an oscillatory folding device and means for operating the same at intervals 105 including an actuating gear, a clutch for throwing the same into and out of operation, a wheel connected with the clutch and with the folding device, a lever also connected with the clutch and a cam wheel for operating the lever.

14. A machine for folding paper pulp laps including an oscillatory folding device and mechanism for operating the same comprising a rotary element connected with the folding device and provided with a recess, 115 an actuating gear, a clutch for connecting the rotary element with the actuating gear, a lever connected with the clutch and movable into and out of the said recess, and a cam wheel for operating the lever.

120 15. A machine for folding paper pulp sheets or laps including an oscillatory folding device, a gear wheel for actuating the mechanism, a pinion connected with the oscillatory folding device, a rack bar meshing with the pinion, a stop wheel provided with a recess and having an eccentrically arranged pin, means for connecting the pin

with the rack bar, a clutch for connecting the stop wheel with the said gear, a lever for actuating the clutch having an arm arranged to engage the recess of the stop 5 wheel, means for urging the lever in one direction and a cam for swinging the lever in the opposite direction.

16. A machine for folding paper pulp sheets or laps including spaced oscillatory 10 folding devices, pinions connected therewith, rack bars meshing with the pinions, a crank shaft connected with the rack bar and means for rotating the crank shaft at intervals.

17. A machine for folding paper pulp sheets or laps including spaced oscillatory folding devices, gears connected with the same and meshing with each other, an arm connected with one of the gears, a crank 20 shaft having a crank element connected with the said arm, and means for rotating the crank shaft at intervals.

18. A machine for folding paper pulp sheets or laps including folding mechanism 25 and means for supporting a sheet comprising a vertically movable frame, rollers carried by the frame, a crank shaft having

crank elements connected with the frame and means for rotating the crank shaft partially at intervals.

19. A machine for folding paper pulp sheets or laps including folding mechanism and means for supporting a sheet comprising a vertically movable frame, rollers carried by the frame, a crank shaft having 30 crank elements connected with the frame and means for rotating the crank shaft partially at intervals, said means including a stop wheel having diametrically opposite recesses and provided with means for connecting it with the crank shaft, an actuating element, a clutch for connecting the actuating element with the said wheel, a lever connected with the clutch and arranged to engage the notches of the said wheel, and a 35 cam wheel provided with a plurality of cams for actuating the lever.

In testimony whereof I affix my signature in presence of two witnesses.

WILLIAM GOODELL.
